UNITED STATES PATENT OFFICE.

PAUL A. BREDSVOLD, OF CHICAGO, ILLINOIS.

DESIGN FOR A REFLECTING LAMP SHADE.

Application filed January 28, 1928. Serial No. 25,061. Term of patent 7 years.

To all whom it may concern:

Be it known that I, PAUL A. BREDSVOLD, a citizen of the United States, residing at Chicago, in the county of Cook and State of Illinois, have invented a new, original, and ornamental Design for a Reflecting Lamp Shade, of which the following is a specification, reference being had to the accompanying drawing, forming a part thereof.

The figure is a side elevation of a reflecting lamp shade showing my new design.

I claim:

The ornamental design for a reflecting lamp shade, as shown.

PAUL A. BREDSVOLD.
